C. C. SHIPP

DAMPER CONTROL FOR RADIATOR BOXES

Filed Aug. 28, 1926

Inventor,
Clarence C. Shipp,
By Mintern & Mintern
Attorneys,

UNITED STATES PATENT OFFICE.

CLARENCE C. SHIPP, OF INDIANAPOLIS, INDIANA.

DAMPER CONTROL FOR RADIATOR BOXES.

Application filed August 28, 1926. Serial No. 132,168.

This invention relates to heating and ventilating units for buildings, particularly those in which a large number of people are congregated, as in school rooms, halls, and the like, that are heated by steam circulating through radiator sections, and wherein fresh outside air is admitted to a box, in which the radiator is wholly or partly contained, and caused to sweep the coils from bottom to top of the radiator. And it further relates to an air-flow control for the above unit comprising a damper in the air intake and a second damper regulating a discharge through the bottom of the box base into the room.

One object of this invention is so to synchronize the opening and closing of the two dampers that as either one is opened, the other will be closed to the same extent.

20 A further object is to provide an adjustment by which the relative movements of the two dampers may be changed and regulated.

The object also is to provide means for manually operating the damper control.

25 I accomplish the above and other objects which will hereinafter appear in the appended description by the mechanism illustrated in the accompanying drawing, in which—

30 Fig. 1, is a perspective view of a radiator housed in a box, having a base connected with an outside air intake, said parts having dampers and damper controls embodying my invention, the radiator box and room-wall being broken away to show said operative mechanism in full open position of the intake damper and closed position of the damper in the base.

Fig. 2, is a like view with the intake 40 damper closed and the other open.

Like characters of reference indicate like parts in the two views.

The radiator sections 3 are of any usual and suitable construction, heated with steam. 45 They are here shown as partly enclosed by a sheet metal box 4 which has a base 5. All, or as many of the sections of the radiator as desired may be included in the box. The above assembly is located near a wall 6 of a room to be heated.

For sanitary reasons the vitiated air next to the ceiling of the room is discharged through a ventilator (not shown) of usual construction, which creates a partial vacuum 55 here utilized to draw in pure outside air

through an air chute 7, which discharges into the base 5 through a sleeve extension which discharges through the side next to the wall, of the base 5 which is open for such connection. The purpose of the sleeve 60 extension is to adjust the length of the chute to the thickness of the wall 6, the thickness of which frequently varies.

The base 5 also has a longitudinal bottom opening which is closed by a metal door or 65 damper 8, hinged to the base under the rear side of the bottom opening.

Hinged to the top of the chute 7 is a damper 9, the lower edge of which in closed position of the damper contacts a rib 10 on 70 the bottom of chute 7.

The usual storm louvers 11, and wire insect screen 12, are provided between the outer end of the chute and damper 9.

Pivoted to ears 2 extending up from the 75 bottom of chute 7 is a lever 13, the upper end of which is connected by a link 14 with ears on the damper 9. A link-bar 15 is also pivoted to lever 13, between link 14 and ears 2, and extending toward the damper 8, it is 80 pivotally attached to a lever 16. The lower end of the lever 16 is pivoted to ears 17 on the chute bottom close to the edge of the bottom opening in base 5. The other end 85 of the lever 16 is connected by an elastic tie 18, here shown as a spirally wound spring, with an eye in the damper 8.

A chain 19 is secured at one end to the free 90 end of lever 16 and it passes thence through a suitable opening in the sleeve forming a part of the air-intake chute, to a pulley 20, thence around a pulley 21, near the top of the radiator box, and thence through the box to the front and outside of the latter, where it terminates with a hand pull 22. 95 The hole in the front of the box through which the chain passes has a narrow slot 23 in its bottom to receive a link and lock the chain at any position by dropping the hand pull 22.

100 Referring to the link-bar 15, its end next to the lever 16 is bent downwardly for better clearance of the body of the bar with the ears below, in the lowered position of the link bar shown in Fig. 2, and this link bar 105 15 is preferably made in two pieces which lap each other and are united by screws or bolts adapted to be removed for the purpose of lengthening or shortening the bar in adjusting it so that either of the two dampers, 110

8 and 9, will be fully open when the other is closed, or may be opened to any desired extent less than full.

To this end each piece of the two-part bar

5 will be formed with a suitable series of bolt-holes. This adjustment of link bar 15 is important when the damper 8 is closed through a spring tie 18, because of the varying tension of such springs.

10 As this invention is capable of variations in form and arrangement I do not desire to limit myself to what is here shown and described, any more than is required by the appended claims.

15 I claim:

1. The combination, with a radiator, of a radiator box, a box base, a damper in the bottom of the box base, a fresh air chute discharging into the box base, a damper in 20 the air chute, a pair of levers pivotally supported one by the air chute, and the other by the box base, a link bar connecting the two levers, a link connecting one of the levers with the damper in the air chute, an elastic tie connecting the other lever with the damper in the box base, and means for moving the last lever in opposition to the pull of the elastic tie on said lever.

2. The combination, with a radiator, a radiator box, a box base, a damper in the bottom of the box base, a fresh air chute discharging into the box base, a damper in the air chute, a pair of levers pivotally supported one by the air chute and the other by the 35 box base, a link bar connecting the two levers, a link connecting one of the levers with the damper in the air chute, an elastic tie connecting the other lever with the damper in the box base, and means for moving the last lever in opposition to the pull 40 of the elastic tie on said lever comprising a manually operated pull chain.

3. The combination, with a radiator, of a radiator box, a box base, a damper in the 45 bottom of the box base, a fresh air chute discharging into the box base, a damper in the air chute, a lever pivotally supported one by the air chute and the other by the box base, a link bar connecting the lever with 50 the damper in the air chute, a second link bar on the other side of the lever from the first pivoted to said lever, means including a spring tie connecting the second link bar with the damper in the bottom of the box 55 base and manually operated means for moving the second link bar in opposition to the spring tie.

4. The combination, with a radiator, of a radiator box, a box base, a damper in the bottom of the box base, a fresh air chute 60 discharging into the box base, a damper in the air chute, a pair of levers pivotally supported one by the air chute, and the other by the box base, a link bar connecting the two levers said link bar being adjustable in its 65 length, a link connecting one of the levers with the damper in the air chute, a spring tie connecting the other lever with the damper in the box base, and a pull chain for moving the last lever in opposition to 70 the spring.

5. The combination, with a radiator, of a radiator box, a box base, a damper in the bottom of the base hinged on the wall side of the base, a fresh air chute discharging 75 into the box base above the damper, a damper in the air chute hinged at its upper edge and swinging downwardly, a pair of levers pivoted at their lower ends to ears one on the bottom of the chute and the other on the 80 box base, a link bar connecting the upper end of one of the levers with ears on the damper in the air chute, a link bar adjustable in its length pivoted at its ends to each of said levers, a coiled spring connecting the outer 85 end of the nearest lever with the damper in the box base, and a chain attached to the outer end of said last lever for manually moving the lever in opposition to the spring.

6. The combination, with a radiator, of a radiator box, a box base, a damper in the base, a fresh air chute discharging into the box base, a damper in the chute, means for simultaneously operating the two dampers, means for adjusting the distance between 95 the dampers by varying the length of the chute, and means for adjusting the relative movements of said dampers at all positions of the dampers.

7. The combination, with a radiator, of a radiator box, a box base, a damper in the base controlling the discharge into the room, a fresh air chute discharging into the box base, a damper in the chute controlling the discharge through the chute, means for simultaneously and manually operating the two dampers, means for adjusting the distance between the dampers by varying the length of the chute, and means for adjusting the relative movements of said dampers 110 at all positions of the dampers.

In testimony whereof I affix my signature.

CLARENCE C. SHIPP.
